Fig. 1 is a perspective view of a flash unit, showing my new design, the unit being illustrated as attached to a camera indicated in broken lines;

Fig. 2 is a front elevational view of one of the blades or leaves of the collapsible reflector portion of the unit;

Fig. 3 is a top plan view of the unit with the reflector blades in fully extended position;

Fig. 4 is a side elevation of the unit likewise with the reflector blades in fully extended position, and with the camera shown in broken lines;

Fig. 5 is a front elevational view of the unit with the reflector blades in fully extended position;

Fig. 6 is a rear elevation of the unit likewise with the reflector blades in fully extended position;

Fig. 7 is a side elevation similar to Fig. 4, on a larger scale and with the reflector blades in totally collapsed position;

Fig. 8 is a front elevational view of the unit with the reflector blades or leaves in the collapsed position of Fig. 7;

Fig. 9 is a front face view similar to Fig. 8 but with the reflector blades or leaves in a partially erected and partially collapsed position;

Fig. 10 is a side elevation of the unit showing the side opposite to that seen in Figs. 4 and 7, with the reflector blades omitted for convenience of illustration, showing the illuminating tube in its retracted position; and

Fig. 11 is a side elevational view similar to Fig. 10 with the illuminating tube in extended position.

The broken line showing of a camera in Figs. 1 and 4 is for illustrative purposes only.

I claim:

The ornamental design for a flash unit, substantially as shown and described.
